LOCOMOTIVE SPOTTER

Oscar L. Coffey, Harvey, Ill., assignor to Whiting Corporation, Harvey, Ill., a corporation of Illinois

Application March 8, 1930. Serial No. 434,246

16 Claims. (Cl. 188—43)

The invention relates to mechanism generally designated locomotive spotters.

In repairing locomotives in railroad shops, it is frequently desired to move a locomotive while it is not in running condition, to bring its wheels, cranks or engine-valves in definite positions for inspection, repair or replacement, and one object of the invention is to provide an improved spotter for this purpose which can be expeditiously 10 locked to the rails of the track at any desired point, to render it operative to move the locomotive. By providing devices which can be expeditiously operated to grip the track-rails so the truck, on which the mechanism is mounted, will 15 be fixedly held, the spotting of the locomotive will be facilitated. Another object of the invention is to provide a pair of gripping devices for the rails respectively, which are conjointly operable to facilitate the operation of spotting the 20 locomotive. Another object of the invention is to provide a gripping device which comprises members to clamp the head of the rail, to effectively secure the truck against slippage on the rails during the operation of the draft-beam to move 25 the load. Another object of the invention is to provide spring counterbalancing means for the draft-beam which is usually mounted to swing vertically on the truck, so that it will be held in or to aid the operator in swinging it into approxi- 30 mate position for connection to a locomotive.

Other objects of the invention will appear from the description.

The invention consists in the several novel features hereinafter set forth and more particu- 35 larly defined by claims at the conclusion hereof.

In the drawings: Fig. 1 is a side elevation of a spotter embodying the invention. Fig. 2 is a detail of one of the connections between a carrying-wheel and the truck-frame to permit the 40 latter to be forced downwardly when it is to be locked to the rails. Fig. 3 is an end elevation. Fig. 4 is a section on line 4—4 of Fig. 1. Fig. 5 is a section on line 5—5 of Fig. 4. Fig. 6 is a central longitudinal section, showing the counter- 45 balancing means for the draft-beam. Fig. 7 is a section on line 7—7 of Fig. 6.

The invention is exemplified in a spotter comprising a truck-frame composed of a pair of channel beams a, a' at either end thereof and a 50 pair of longitudinal channel beams a^2 , and a bottom-plate a^5 , all rigidly secured together, and a pair of brackets a^3 which are secured on the beams a, a' , and support suitable reducing gearing driven by an electric motor b for operating 55 the draft-beam c longitudinally. Said beam is

provided at either end with a draft-bar c' which is adapted to engage or to be coupled to the locomotive. This gearing (Fig. 7) comprises a pinion b' on the motor-shaft, a chain b^2 driven by said pinion, a gear b^3 driven by said chain, a shaft b^4 journalled in a housing b^5 which is fixed to lugs a^{30} on one of the brackets a^3 , a worm b^6 fixed to shaft b^4 in the housing, a gear-wheel b^7 driven by worm b^6 and fixed to a transverse shaft b^8 which extends transversely through and is journalled in 60 brackets a^3 , a pinion b^9 fixed to one end of said shaft, a gear b^{10} meshing with pinion b^9 and fixed to a transverse shaft b^{11} which is journalled in bearings b^{12} on brackets a^3 , a pinion b^{13} fixed to shaft b^{11} between brackets a^3 and meshing with a 65 rack-bar c^2 which is fixed to the bottom face of the I-beam c . Motor b is mounted on the top of housing b^5 .

The truck is provided with a pair of carrying wheels d at one end thereof and connected by 70 an axle d' and at its other end with a similar pair of wheels d , similarly connected by an axle d' . These wheels permit the spotter to travel over a track formed by rails g laid in the floor of the shop. Each of these axles is mounted in 75 a pair of brackets d^2 which are connected to the truck-frame by pivot-pins d^3 which are held in lugs d^4 fixed to one of the channel beams a' . Each bracket d^2 is normally held in position to hold the truck-frame raised by a spring-pres- 80 sure device, comprising a bolt e which is pivot- 85 ed at e' to a bracket d^2 , and extends through one pair of beams a, a' , and a coil-spring e^3 applied to a washer e^4 adjustably held on the inner end of the bolt by nuts e^5 , so that the 90 force of the springs will be applied to swing the brackets d^2 so as to raise the truck-frame relatively to the wheels d . Toothed shoes f are secured to the bottom faces of the beams a' over the rails g of the track, and these yielding con- 95 nections between the truck-frames of the wheels d are provided to permit the truck-frame to be forced downwardly to bring the shoes f , which serve as rail-gripping members, into engagement with the tread of the rails. Normally, these 100 springs lift the truck-frame to hold the shoes f off the rails, so that the spotter may be moved along the rails to any point desired, and the gripping mechanism hereinafter described is adapted to force the frame downwardly to force 105 shoes f against the rails g .

A pair of devices are provided at either end of the truck for engaging the underside of the heads of the rails to force the truck-frame downwardly, and cause the spotter to be locked to the 110

rails against movement along the rack g , when the spotter is to be used to move the locomotive or car. Each of these devices comprises a lever h which is provided with a jaw or hook h'' at its lower end for engaging the underside of the head of one of the rails, and is adapted to be swung outwardly of the rails and thence downwardly when the truck is to be locked and inwardly and upwardly when the truck is to be released from the rails. Each lever h is bodily movable as well as pivotally, for this purpose. Each lever h is composed of dual members or bars, and has connected thereto a fulcrum pin h' which passes through the lever-members and through the upper end of a vertically extending link h^2 . The lower end of link h^2 is connected by a pivot pin h^3 to the outer end of a horizontally extending link h^4 , the inner end of which is pivoted on a pin h^5 which is fixedly held in and between a pair of the beams a, a' . Said beams are spaced apart by blocks a^6 to provide a space for the working of levers h , links h^2 and h^4 . Bottom plate a^5 extends under the truck-frame and is fixed to beams $a, a',$ and a^2 . The outer ends of links h^4 are adapted to rest on said plate when the levers h are lowered. Each pair of gripping devices for the rails respectively is conjointly operable so that both sides of the truck may be simultaneously locked and released. The upper ends of each pair of levers h are adapted to be drawn together by a cross-shaft k which is provided at either end with a hand-wheel k' by which it may be turned. Said shaft is provided with a screw k^2 for operating a nut k^3 which is provided with pivot-studs k^4 which extend into the members of one of the levers h . Shaft k also extends and is slideable through a collar k^5 which is provided with studs k^6 which are pivoted in the members of the other lever h of the pair of conjointly operable clamping devices. Collar k^5 is positioned on the shaft k between collars k^7 and k^8 which are adjustably secured to the shaft. A spring k^9 is coiled around shaft k between collars k^5 and k^8 to normally press the upper end of the lever h which is pivoted to collar k^5 against collar k^7 . This construction provides a yielding operative connection between shaft k and one of the levers h . Shaft k and the upper end of each lever h extend between standards which are fixed to the beams a, a' and are composed of angle bars or plates l fixed on top faces of beams a, a' , vertical bars l' fixed to the angle bars, and inclined brace bars l'' . The upper ends of bars l' are secured together by bolts l^3 which pass through spacing collars l^4 . A roller m is mounted at the upper end of each member of lever h , and is adapted to ride on the inner edge of the brace bar l'' to control the movement of the upper ends of levers h and bodily movement of shaft k during the spreading of the upper ends of the levers h to release truck-frame. Fulcrum pins h' between links h^2 and levers h project from the levers and are adapted to ride on inclined bars n which are secured to the inner faces of angle bars l , to control the outward lateral movements of the fulcrum pins h' , during the outward movement of the upper ends of levers h to withdraw them from the rail-heads.

The beam c is supported so it can tilt vertically in the truck-frame to permit either of its ends to be raised or lowered for connection to the locomotive at the desired point and to permit the truck-frame to be raised or lowered for locking and unlocking, while the beam is coupled to the locomotive and during the movement of the locomotive by the beam. For this purpose the

rack-bar is confined laterally between a pair of plates o which are pivotally held on the shaft b^{11} inside of the brackets a^3 . Rollers o' guide the top surface of the beam c and hold rack-bar c^2 in engagement with pinion b^{13} , so that the beam and rack-bar can be operated longitudinally to move the locomotive while the truck-frame is locked to the rails. To normally hold the beam c horizontal, spring counterbalancing devices are applied thereto, which will permit the beam to tilt, but will normally hold or tend to hold it in horizontal position and aid in lifting the beam. When the beam is extended almost entirely to one end of the truck, the preponderance of weight at one side makes it difficult for the operator to lift it without such counterpressure. These counterbalancing devices are provided for resisting the vertical tilting of the beam in opposite directions respectively. Pins o^4 are pivoted in and extend between the plates o , and pins o^5 are held in and extend between brackets a^3 . Bolts o^6 extend through one of the pins o^5 and one of the pins o^4 . The inner ends of these bolts are provided with heads which normally engage one of the pins o^4 , and springs o^7 are held on outer ends of the bolts o^6 by nuts o^8 and bear against washers o^9 which abut against the pin o^5 , so that when the bar is tilted in either direction, one of the pins o^4 will cause one of the springs o^7 to be compressed to assist the operator in restoring the beam to its horizontal position. A bail p is fixed to the upper end of plates o to receive a hook from a crane whereby the spotter can be transferred from one track to another.

The operation will be as follows: Normally, the rail gripping devices for securing the truck against movement along the rails will be in position indicated in dotted lines of Fig. 4. At such time, the jaws on the lower ends of levers h will be above and inwardly of the rails, the truck-frame will be held raised by the springs e^3 , and the shoes f will be raised off or clear the rails so the truck will be free to be pushed to the desired position on the track where one of its draft-bars c' will be coupled to the locomotive. The operator will then rotate the hand-wheels k' on the shafts k , to lock the truck-frame against movement along the rails. The rotation of each shaft k will draw the nut k^3 and collar k^5 thereon together. During the initial rotation of shaft k , the rollers m , riding on the braces l^2 , will control the bodily lowering of levers h into the recesses in the floor at the inner sides of the rails g until the links h^4 rest on bottom-plate a^5 . The continued rotation of the shaft will draw nut k^3 and collar k^5 together, and this will move the upper ends of the levers h on their fulcrum pins h' to swing inwardly so their jaws h'' will swing outwardly and pass under the heads of the rails and interlock therewith. The continued movement of the shaft k will cause the levers to fulcrum on the rail-head at jaws h'' and through links h^2, h^4 will apply downward pressure on the bottom plate a^5 to force the truck-frame downwardly until the shoes f , which serve as jaws coacting with the lower jaws, will grip the top of the rail. The truck-frame will then be securely clamped to the rails. Each of the shafts k will be operated in this manner to secure both ends of the truck-frame to the rails, so the frame cannot be tilted on the rails. With the truck-frame thus secured, the motor B may be operated to slowly move the locomotive to the desired spot through the reduction gearing which will operate the beam c longitudinally to move the locomotive.

When the spotter is to be moved along the rails, each shaft k will be reversely turned to spread the nut k^3 and the collar k^7 . This will cause the levers h to initially fulcrum on the bars n so the jaws h'' at their lower ends will swing inwardly until they clear the head of the rail; whereupon levers h will be released from the rails, and this will permit the springs l^3 to lift the truck-frame, so that jaws or shoes f will clear the rails. The continued operation of the shaft k will bring rollers m into engagement with the inclined edges of braces l^2 and cause them to ride upwardly to bodily raise the levers h above the rails. During this movement fulcrum pins h' will ride on bars n to control the jaws h'' against outward movement. The inward movement of the upper ends of the levers, during the gripping operation, is positively effected by nut k^3 and collar k^7 . Spring k^9 yieldingly operates collar k^5 during the spreading of the upper ends of the levers to permit them to be freely controlled by braces l^2 . The shaft k is carried by levers h and is bodily movable so it can rise and fall with the levers and so it will be free to be positioned endwise by nut k^3 and rollers m .

When the draft-beam is uncoupled from the locomotive and is drawn out to an off-center position, the preponderance of weight at one end will tend to tilt the beam vertically, but the spring counterbalancing devices will resist this tilting and aid the operator in lifting the beam into, or retaining it in, approximately horizontal position, so that one of its ends will be at the proper height for connection to the locomotive. The invention exemplifies a spotter which is equipped with a plurality of rail-gripping devices which can be conjointly operated to quickly clamp the truck to both rails of a track or to release it therefrom; in which the truck-frame may be effectively locked against movement along the rails by devices comprising jaws for clamping the rail head; in which the draft-beam is pivotally movable and counterbalancing means is applied to aid the operator in lifting the beam to its approximately horizontal position.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In combination, a truck-frame, means to travel on a pair of rails, to which the frame is connected for relative vertical movement, spring means for holding the frame normally raised, and a device for clamping one of the rails to secure the frame against movement, comprising means for engaging said rail and forcing the frame downwardly.

2. In combination, a truck-frame, means to travel on a pair of rails, to which the frame is connected for relative vertical movement, spring means for holding the frame normally raised, and a device for clamping one of the rails to secure the frame against movement, comprising a jaw to engage the rail under its head and force the frame downwardly.

3. In combination, a truck-frame, means to travel on a pair of rails, to which the frame is connected for relative vertical movement, spring means for holding the frame normally raised, and a device for clamping one of the rails to secure the frame against movement, comprising

a shoe on the frame adapted to engage the tread of the rail and a jaw to engage the rail under its head and force the frame downwardly.

4. In combination, a truck-frame, means to travel on a pair of rails, to which the frame is connected for relative vertical movement, spring means for holding the frame normally raised, and a device for clamping one of the rails to secure the frame against movement, comprising a lever to engage the rail under its head and force the frame downwardly.

5. In combination, a truck frame, wheels to travel on a pair of rails, to which the frame is connected for relative vertical movement, spring means for holding the frame normally raised, means on the frame to engage the tread of one of the rails, and a device for engaging the rail and forcing the frame downwardly to clamp said frame on the rail.

6. In combination, a truck frame, wheels to travel on a pair of rails to which the frame is connected for relative vertical movement, spring means for holding the frame normally raised, means on the frame to engage the tread of one of the rails, a lever fulcrumed on the frame for engaging the rail, and means for shifting the lever to force the frame downwardly and securing it to the rail.

7. In combination, a truck-frame provided with wheels to travel on a pair of rails and movable radially relatively to the wheels, and a device for securing the frame to one of the rails, mounted on the frame, and comprising a shoe on the frame, an element adapted to pass under the head of the rail, and means for shifting the element to engage the rail and force the shoe and the frame downwardly, relatively to the wheels, said shoe and element being movable to clear the rail while the truck wheels rest on the rails.

8. In combination, a truck frame provided with wheels to travel on a pair of rails and movable radially relatively to the wheels, and a device for securing the frame to one of the rails, mounted on the frame, and comprising a shoe on the frame, a lever adapted to pass under the head of the rail, and means for shifting said lever to engage the rail and force the shoe and the frame downwardly, said lever and shoe both being movable to clear the rails while the wheels are on the rails.

9. In combination, a truck-frame provided with wheels to travel on a pair of rails and movable radially relatively to the wheels, and a device for securing the frame to one of the rails, mounted on the frame and comprising a lever on the frame having a vertically movable fulcrum and provided with means to pass under the head of the rail and means for bodily and pivotally shifting the lever to force the frame downwardly.

10. In combination, a truck-frame provided with means to travel on a pair of rails, and a device for securing the frame to one of the rails, mounted on the frame and comprising a lever, a fulcrum-link between the lever and the frame, a jaw on the lever to engage the rail, and means for shifting said lever.

11. In combination, a truck-frame provided with means to travel on a pair of rails, and a device for securing the frame to one of the rails, mounted on the frame and comprising a lever, a pair of connected links, to one of which the lever is pivoted and the other of which is pivoted to the frame, a jaw on the head of the rail and for forcing the frame downwardly.

12. In combination, a truck-frame, provided with means to travel on a pair of rails, and a pair of devices for securing the frame to rails respectively, each comprising a lever having a movable fulcrum and provided with a jaw to engage the head of a rail, a shaft between said levers, provided with means for shifting the levers, and a yielding connection between one lever and the shaft. 86
13. In combination, a truck-frame provided with means to travel on a pair of rails, a device mounted on the frame for securing the frame to one of the rails comprising a jaw, means for shifting the jaw to pass under and engage the underside of the head of the rail and to move laterally and upwardly to withdraw the jaw from the rail, and means on the frame to engage the tread of the rail. 85
14. In combination, a truck-frame provided with wheels to travel on a pair of rails, a pair of rail-gripping devices, each comprising a bodily and pivotally movable lever provided with a gripping jaw at its lower end, guides for controlling the upper end of the levers, and a shaft connected to shift and supported by the upper ends of the lever. 90
15. In combination, a truck-frame provided with wheels to travel on a pair of rails, a pair of rail-gripping devices, each comprising a bodily and pivotally movable lever provided with a gripping jaw at its lower end, guides for controlling the upper end of the levers, and a shaft connected to shift and supported by the upper ends of the lever. 95
